UNITED STATES PATENT OFFICE.

ARLINGTON MOORE, OF BOSTON, MASSACHUSETTS, ASSIGNOR TO CLARKE-MOORE CORPORATION, OF WILMINGTON, DELAWARE, A CORPORATION OF DELAWARE.

PAPER CONTAINER.

Application filed August 19, 1920. Serial No. 404,558.

To all whom it may concern:

Be it known that I, ARLINGTON MOORE, a citizen of the United States, residing at Boston, in the county of Suffolk, State of Massachusetts, have invented certain new and useful Improvements in Paper Containers; and I do hereby declare the following to be a full, clear, and exact description of the invention, such as will enable others skilled 10 in the art to which it appertains to make and use the same.

The present invention relates to paper containers, that is, to containers made of any suitable fibrous stock whether paper or 15 resembling paper, and particularly to the closure therefor. The container may be in the form of a can with a cylindrical side wall, or in any suitable polygonal or curved 20 form, wound or formed in any suitable way. The paper stock may be single or multiple 25 ply, with or without incorporating a binder, and the container may be coated with paraffin or the like, and may have a paper covering or advertising label.

The closure of the present invention provides an effective seal suitable for either the 30 top or bottom of the container, or both, and comprises a cap having a wall which is folded together with the side wall of the 35 container, preferably inwardly, to form a bead. The folds of the bead may have opposed arched portions to resist relative 40 movement between adjacent folds and consequent displacement. Preferably the bead is angular in cross section and the arched 45 portions arranged diagonally thereof, the portions on the diagonal line at one side of the center of the bead being opposed to those on the diagonal line at the other side thereof. Where also the bead is highly compressed and practically solidified, the cap, 50 as well as the folds of the bead are rigidly set and the container is tightly sealed against the ingress of moisture and foreign 55 matter and the egress of the contents.

The side wall of the container may be provided with a hem which is convoluted to form the core of the bead and an anchor, the end of the wall of the cap being secured 60 in the bead between the core and folds thereof, in which case the opposed arched por-

tions of the folds act also to grip the end of the wall of the cap.

The invention further comprehends as another of its parts a paper container having 55 a side wall and a closure therefor comprising a cap having a wall folded, preferably inwardly, together with the side wall to form a bead, the bead having a cap-retaining groove, preferably in the inner wall thereof, and a binding cap in the groove to preclude the displacement of the folds of the bead; and, if the bead be highly compressed and practically solidified so as to be rigidly 60 set, the folds are so maintained by the binding cap. The bead may be formed in contact with, and the cap-retaining groove therein adjacent, the closure cap, and a portion of the folds may be arched toward the groove to stiffen the resistance of the latter 65 to displacement. Where the bead is angular, portions of the folds thereof are diagonally arched toward the groove, preferably from the outer edge of the bead diagonally toward the groove in the lower inner corner thereof; and the arched portions on the diagonal line at one side of the center of the bead may form the groove and oppose like portions on the diagonal line at the other side 70 of the center to resist the displacement of the folds and to stiffen the groove against displacement. Moreover, where the bead is in contact with the closure cap, and the groove adjacent thereto, the binding cap 75 preferably is superimposed upon the closure cap, thus forming a double cap and serving not only to reinforce the closure cap against longitudinal displacement under greater pressure, but also the container against deformation. The closure cap may have an 80 opening therein which may be sealed by the binding cap. And so also the side wall of the container may have a recess and the wall of the cap a portion in the bead complementary to the recess for interlocking the 85 walls, in which construction the binding cap 90 serves also to compress the folds of the bead in the recess, and in addition insures the continuance of the gripping effect of the latter. The portion of the wall of the cap 95 which is formed, in folding, complementary to the recess in said side wall may also form

a recess, preferably an inner recess, in which the folds of the bead may be anchored. In this construction the binding cap also acts to retain the folds of the bead in the recess in which they are anchored.

5 In the accompanying drawing illustrating the invention in application, as an example, to a cylindrical container of single 10 ply stock, the figure is a view of the container partly in section and partly in elevation.

The container has a cylindrical side wall 1 of suitable thickness and surface finish and top and bottom closures 2 and 3 respectively.

15 The closure comprises a cap 4 having a wall 5 which is folded together with the side wall 1 of the container to form a bead 6. The side wall 1 has a recess at 7 in the 20 bead in which a portion of the wall 5 of the cap 4 is fitted forming an inner recess 8, and the folds of the bead are anchored therein. The side wall 1 is provided with a hem 9 which is convoluted to form the core 25 10 of the bead, and the end of the wall of the cap is secured at 11 between the core and folded portions thereof.

The bead has a cap-retaining groove 12 adjacent the closure cap 4 formed by 30 diagonally arching the folds as at 12, 13, and 14, the remainder of the folds being likewise diagonally but oppositely arched as at 16, 17, and 18. The cap 4 may have an opening as at 19, and the groove a binding 35 cap 20 therein superimposed upon the closure cap 4 and serving either to seal the opening 19, as shown in the top closure, or to form a double cap as in the bottom closure. The inner wall 21 of the bead is 40 tapered inwardly to guide the binding cap as it is forced into position.

Portions of the closure of the container, particularly the bead 6, are subjected in forming to a pressure of about 4000 to 6000 45 pounds per square inch, under which the parts are rigidly set to gage dimensions and become practically solidified.

The closure constructed as above described and the container wall are thoroughly reinforced for strength to withstand unusual 50 pressures in handling or in shipment tending to break down the seal or to deform the container, for not only are the folds of the bead gripped in the recess 7, and anchored 55 in the inner recess 8, but they are retained in these recesses by the binding cap 20 securely held in the groove 12 which is stiffened against displacement by the diagonally arched folds directed toward it. Furthermore, 60 where the groove 12 is formed of diagonally arched portions of the folds of the bead at one side of its center, the latter being opposed by similarly arched portions at the other side of the center, the folds are 65 secured against displacement and the end

of the wall of the cap may be gripped at least at two diagonal points to further secure it in place in the bead.

Having thus described my invention, what I claim is:

1. In a paper container, a side wall, and a closure therefor comprising a cap having a wall folded together with said side wall to form a bead, and a hem on said side wall which is convoluted to form the core 70 of the bead, the end of the wall of the cap being secured in said bead between the core and folds thereof, and said folds having opposed arched portions to resist their displacement and to grip the end of the wall 80 of the cap.

2. In a paper container, a side wall, and a closure therefor comprising a cap having a wall folded together with said side wall to form a bead, said bead having a cap-retaining groove and portions of the folds 85 thereof arched toward said groove to stiffen the resistance of the latter to displacement, and a binding cap in said groove.

3. In a paper container, a side wall, and a closure therefor comprising a cap having a wall folded inwardly together with said side wall to form an angular bead, said bead having a cap-retaining groove and portions 90 of its folds diagonally arched toward said groove, and a binding cap in said groove.

4. In a paper container, a side wall, and a closure therefor comprising a cap having a wall folded inwardly together with said side wall to form an angular bead in contact with said cap, said bead having a cap-retaining groove at the lower inner corner thereof and adjacent the closure cap and a portion of its folds arched from an outer edge diagonally toward said groove, and a 100 binding cap in said groove and superimposed upon the closure cap to form a double cap.

5. In a paper container, a side wall, and a closure therefor comprising a cap having a wall folded together with said side wall to form an angular bead, the folds of the bead having arched portions arranged diagonally thereof, said arched portions on the diagonal line at one side of the center 115 of the bead forming a cap-retaining groove and being opposed by like arched portions on the diagonal line at the other side of the center, to resist the displacement of the folds, and to stiffen the groove against displacement; and a binding cap in said groove.

6. In a paper container, a side wall, and a closure therefor comprising a cap having an opening and a wall folded inwardly together with said side wall to form a bead in contact with said closure cap, said bead having a cap-retaining groove adjacent said cap and a portion of the folds thereof arched toward said groove to stiffen the resistance 125 130

of the latter, and a binding cap in said groove and superimposed upon said closure cap to seal the opening therein.

7. In a paper container, a side wall having a recess, and a closure for the container comprising a cap having an opening therein, and a wall folded inwardly together with said side wall to form a bead in contact with said closure cap and a portion

complemental to said recess in said bead for 10 interlocking said wall; said bead having a cap-retaining groove in the inner surface thereof and portions of its folds arched toward said groove, and a binding cap in said groove for retaining the folds of the bead 15 in said recess.

In testimony whereof I affix my signature.
ARLINGTON MOORE.
